UNITED STATES PATENT OFFICE

2,645,036

WALNUT DEHYDRATOR

John M. Frantz, Modesto, Calif.

Application August 17, 1951, Serial No. 242,351

2 Claims. (Cl. 34—213)

1

This invention comprises novel and useful improvements in drying devices, and more particularly pertains to a device for dehydrating nuts and the like.

An important object of this invention is to provide a device which may be economically manufactured and operated, for dehydrating nuts and the like.

Another object of this invention is to provide a drying device of the type employing a heater to heat the air passing therethrough, which device will utilize the heated, moisture laden exhaust air to preheat the air entering the drying device.

A further object of this invention is to provide a drying device in which the articles being dried may be continuously or intermittently fed and removed therefrom, and in which the articles, just prior to removal, pass adjacent the heated air entering the casing to complete the dehydration thereof.

An important feature of this invention resides in the provision of a casing having air inlet and outlet openings adjacent the lower and upper ends thereof, respectively, and in which the air is heated adjacent the lower end of the casing and forced therethrough, together with a duct on the outlet opening for directing the discharged air through an intervening open air space to the adjacent air inlet opening, whereby the heated moisture-laden discharged air preheats the air entering the inlet opening.

Another feature of this invention resides in the provision of a drying device, constructed in accordance with the foregoing features, in which a foraminous article support member is disposed in the casing, above the bottom thereof, and which support member has a bottom inclined upwardly from an article discharge opening, and upwardly diverging sides which form a reduced article passageway adjacent the discharge opening to facilitate the circulation of air around the article passing through the device.

These, together with various ancillary objects and features are attained by this device, a preferred embodiment of which is illustrated in the accompanying drawings wherein:

Figure 1 is a rear elevational view, parts being broken away and shown in section to illustrate details of construction;

Figure 2 is a vertical sectional view, taken upon the plane of the section line 2—2 of Figure 1;

Figure 3 is a horizontal sectional view, taken in the plane of the section line 3—3 of Figure 2;

Figure 4 is a fragmentary horizontal sectional

2

view, taken on the plane of the section line 4—4 of Figure 2; and

Figure 5 is a fragmentary vertical sectional view, taken on the plane of the section line 5—5 of Figure 1.

Reference is now made more specifically to the accompanying drawings, wherein like numerals designate similar parts throughout the various views, and in which the drying device is indicated generally by the numeral 10.

The drying device comprises a casing having a front wall 12, rear wall 14, and opposing side walls 16 which are secured together, as by angle iron standards 18. The bottom wall 20 is secured to the front wall and the side walls, and a rearwardly extending air inlet duct 22 communicates by means of an opening 24, in the rear wall 14 with the casing adjacent said bottom wall. The entire casing is supported on a frame 26 which is disposed on the upper ends of the longitudinally adjustable legs 28, whereby the height of the casing may be adjusted to facilitate the positioning of receptacles therebelow.

A hood including an upwardly and rearwardly inclined top 30 and downwardly diverging sides 32, is secured to the upper end of the casing, an article inlet opening 34 being formed in the top to permit the feeding of articles into the upper end of the casing. The opening 34 is closed by a sliding closure 36 mounted on guides 38, and a dispensing spout 40, is secured to the top 30, in registry with the opening 34 therein. The dispensing spout includes an upper relatively stationary section 42, and a lower, angularly offset section 44, horizontally movably connected thereto, as at 46, the lower section being adjustably moved by means of handles 48 which extend through a suitable opening 50 in the hood.

It is contemplated that the air be heated as it enters the casing, and for this purpose there is provided a plurality of heaters, such as the fuel burners 52 illustrated which are connected to a suitable source (not shown) by conduits 54, the heaters being positioned in the inlet duct 22.

A foraminous heat diffusing member 56, of thermally conductive material, is secured within the casing, above the inlet opening 24, to evenly distribute the heated air across the lower end of the casing. As clearly shown in Figure 2 the duct 22 projects into the casing and the member 56 is cut away at 57 to facilitate a smooth distribution of heated air.

In the illustrated form of the drying device, there is provided a double bin dehydrator, the casing being divided by a vertical panel 58 which

terminates above the foraminous member 56 and below the top wall 30 of the hood. The lower end of each bin is closed by a foraminous article support member 60 comprising a bottom 62 inclined upwardly and rearwardly from an article discharge opening 64, and sides 66 which diverge upwardly and rearwardly, to thereby form a chute such that the articles will be gravity actuated toward the opening 64. As will be noted, the individual article support members 60, adjacent the discharge openings form relatively constricted passages whereby the articles passing therethrough will be more uniformly exposed to the heated incoming air to complete the dehydration thereof. The openings 64 are closed by suitable sliding doors 68, mounted for movement in the guides 10.

The air is exhausted from the upper end of the casing by means of a suitable blower 72, mounted, as by brackets 74, adjacent the discharge opening 76 in the rear wall 14 of the casing. A foraminous air diffusing screen (not shown) is disposed in the casing below the discharge opening 76 to effectuate more uniform movement of the air through the casing, and an angulated, downwardly directed discharge duct 78 is secured to the casing in registry with the opening 76. Thus, the heated, moisture-laden air, exhausted from the casing by the blower 72 passes through the intervening space between the discharge duct 78 and upturned inlet end of the inlet duct 22, and the surrounding air is heated thereby. As is well known, cooling of the moisture-laden air, as by the surrounding air, will cause the moisture to precipitate therefrom. The air entering the inlet duct 22 comprises a mixture of the preheated surrounding air, and the partially cooled exhaust air, which has lost a portion of its moisture content in the cooling process, and, consequently, a portion of the heat supplied to the air entering the casing is effectively removed, thereby improving the efficiency of the device.

As is best shown in Figure 5, the longitudinally adjustable legs include tubular standards 80, which are secured as by welding, to the frame 26, coaxial posts 82 being telescopically received in the standards and adjustably locked thereto as by the pin and slot connection 84.

The fuel supplied to the burners 52 is regulated by a valve 86 (see Figure 1) which valve is thermostatically controlled, as by thermostat 88, to maintain the temperature of the air within the casing within the desired range.

From the foregoing, it will be seen that articles may be continuously or intermittently fed through the opening 34 and removed through opening 64, the article support member being of such a construction that the articles are gravity actuated toward the article discharge opening 64. The articles fed to the device may be deposited in either bin, as by proper manipulation of the spout adjusting handle 48, which causes horizontal swinging movement of the lower section 44 of the spout.

The air entering through the inlet duct 22 is heated by burners 52 to the proper temperature, determined by the thermostat 88, the air being forced through the articles in the casing by means of the exhaust blower 72. The heated, moisture

laden air is directed by the duct 78 through the intervening air space, toward the inlet duct 22, whereby a portion of the heat in the exhaust air is recouped, in a manner hereinbefore set forth. 5 It is thought that the advantages of this invention will be readily appreciated by those skilled in the art, and the value of the same to walnut producers will be clearly understood.

From the foregoing, the construction and operation of the device will be readily understood and further explanation is believed to be unnecessary. However, since numerous modifications and changes will readily occur to those skilled in the art, it is not desired to limit the invention to the exact construction shown and described; and accordingly, all suitable modifications and equivalents may be resorted to, falling within the scope of the appended claims.

Having described the invention, what is claimed 20 as new is:

1. A drying device comprising a casing having an air inlet opening adjacent its lower end and an air outlet opening adjacent its upper end, means in said casing for heating the air entering 25 said inlet opening, blower means for forcing air through said casing, an article discharge opening in the front side of said casing above the bottom thereof, and a foraminous article support member in said casing, said support member including a bottom inclined upwardly away from said opening and upwardly and rearwardly diverging sides, and a vertically inclined dispensing chute horizontally, swingably mounted adjacent the upper end of said casing for directing the articles discharged therein onto said support member; and a downwardly directed duct on said outlet opening, said duct terminating in vertically spaced relation to said inlet opening.

2. A drying device comprising a casing having an air inlet opening adjacent its lower end and an air outlet opening adjacent its upper end, means in said casing for heating the air entering said inlet opening, blower means for forcing air through said casing, a foraminous article support member in said casing, and a vertically inclined dispensing chute horizontally swingably mounted adjacent the upper end of said casing for directing the articles discharged therein onto said support member, and a downwardly directed outlet duct on said outlet opening, said duct terminating in vertically spaced relation to said inlet opening.
